Charles E. Hutto
ATTORNEY.

UNITED STATES PATENT OFFICE

MARDEN C. HUTTO, OF DETROIT, MICHIGAN

MULTIPLE-CYLINDER GRINDER

Application filed August 9, 1926. Serial No. 128,024.

This invention relates to double ended or multiple cylinder grinders and the object of the invention is to provide a grinder for grinding a plurality of cylindrical apertures simultaneously.

Another object of the invention is to provide a grinder for simultaneously grinding spaced apertures in alignment and to an exact diameter.

Another object of the invention is to provide a double ended or multiple grinder in which the diameter of the grinding stones in any cylinder may be adjusted independently.

A further object of the invention is to provide a plurality of independently adjustable cylinder grinders adapted to be connected together by yokes of different lengths by which the distance apart of the grinders may be varied.

These objects and the several novel features of the invention are hereinafter more fully described and claimed and the preferred form of construction by which these objects are attained is shown in the accompanying drawings in which—

Fig. 1 is a longitudinal section through a double ended cylinder grinder embodying my invention.

Fig. 2 is an enlarged section taken on line 2—2 of Fig. 1.

The grinder comprises a yoke or connector 1 having threaded ends 2. A tubular body member 3 is threaded onto one end of the yoke 1 and a similar body member 4 is threaded onto the opposite end of the yoke 1. These body members 3 and 4 are each provided with a series of three longitudinal slots in which the stone holders 5 are positioned as shown in Fig. 2. Extending longitudinally of each body member is a shaft 6 which at one end is threaded into a cone 7. This cone is movable longitudinally of the respective body member and a dowel pin 8 is provided extending through the respective body member and engaging in a keyway provided therefor in the cone to prevent the cone from rotating in the body. A cone 9 is rotatably mounted on the opposite end of each shaft 6 and a knob 10 is secured to the shaft 6 at the left 50 of Fig. 1 while the shaft 6 at the right end

of Fig. 1 is provided with an enlarged head 11 having a screw driver slot by which the shaft may be turned. The stone holders 5 are preferably formed from die cast metal and are provided with angular faces 12 which fit the faces of the cones 7 and 9. A grinding stone 13 is embedded in each stone holder 5 and the stone holders are held in position in the several slots by means of annular coiled springs 14 fitting the annular grooves 15 in the body members and notches 16 in the stone holders 5. In this manner the stone holders are properly seated on the cones so that as the cones are drawn together the stone holders and grinding stones are moved radially outwardly. The body member 3 at the right of Fig. 1 is provided with an enlarged cup shaped end 17 having a bayonet notch 18 therein into which a driving member may be inserted for rotating the entire double ended grinder.

This device is utilized for simultaneously grinding two cylindrical apertures in alignment and to an exact diameter and for the purpose of illustration I have shown two bushings 19 in which the apertures therethrough may be ground in alignment. The tool is first positioned in the bushings 19 as shown in Fig. 1 it being understood that the bushings 19 are to be held in a fixed support so that they cannot move. At this time by inserting a screw driver in the slotted head 11 at the right of Fig. 1 the shaft 6 may be threaded into the cone 7 thus drawing toward each other to move the stone holders outwardly until the grinding stones contact the inner wall of the aperture to be ground. It is to be noted that both cones 7 and 9 and the shaft 6 are movable freely longitudinally of the central bore 20 of the body member. This provides a floating action of the cones so that the pressure is evenly distributed over the cones thus allowing the grinding stones to be evenly expanded. At the opposite end the knurled knob 10 may be turned which turns the respective shaft 6 and threads it into the respective cone 7 thus drawing the cones together and expanding the grinding stones in the same manner as at the opposite end of Fig. 1. At this time the driving mem- 100

ber may be engaged in the notch 18 for rotating the entire grinder in the bushings 19. As the device is rotated it should also be moved back and forth longitudinally so that the 5 grinding stones grind the entire inner surface of the bushings. As the grinding stones begin to free themselves they may be expanded further by rotation of the knob 10 and the screw head 11 until the bushings are ground to size. At this time the knob 10 and screw 10 head 11 are turned in the opposite direction to unthread the shafts 6 from the cones 7 thus allowing the cones to move apart under pressure by the coiled springs 14 which also 15 tend to firmly seat the stone holders on the cones. This reduces the diameter of the grinding stones and the entire device may be then withdrawn from the bushings. Yokes or connectors 1 of different lengths may be 20 used depending upon the distance apart of the apertures to be ground and these yokes may be readily removed and replaced by means of the threaded ends 2. I have described the members 13 as grinding stones 25 but these may be abrasive or cutting devices for wearing away or cutting the metal to an exact diameter.

Although the drawings illustrate an apparatus in which two grinder bodies are shown, 30 each of which is provided with abrasive members or grinding stones for working the cylindrical surface of a bushing, it is to be understood that this invention is not limited in its use to a tool having two grinder units, 35 but is intended to comprehend a tool of this character having a plurality of such grinding units.

The bushings 19, 19, are intended to represent generally two cylindrical surfaces of 40 any structure in which these two surfaces are arranged in definite relation to each other. These surfaces are represented in Figure 1 as formed in the two sleeves 19, 19, and these are maintained in a definite relation relative 45 to each other, so that they are practically integral, by means of a frame consisting in the present case of a base 21 and two pedestals 22 rising from opposite ends of this base, each containing an opening which receives 50 one of the bushings 19.

From the foregoing description it becomes evident that the device is very simple and efficient in operation, will not easily get out of order, provides a means for simultaneously grinding two spaced apertures in alignment and to an exact diameter and provides 55 a device which accomplishes the objects described.

Having thus fully described my invention, 60 its utility and mode of operation, what I claim and desire to secure by Letters Patent of the United States is—

1. A grinder for simultaneously grinding a plurality of cylinders in axial alinement, 65 comprising a plurality of body members ar-

ranged axially in line and each adapted to operate in one of said cylinders; grinding stones mounted on each of said body members and adapted to work on the bore of one of said cylinders independently of the work of the stones of another body member on another cylinder, a yoke rigidly connecting adjacent body members, and means arranged on each of said body members for positively radially adjusting the stones thereon independently of the adjustment of the stones on another body member. 75

2. A grinder for simultaneously grinding a plurality of cylinders in axial alinement, comprising a plurality of body members arranged axially in line and each adapted to operate on one of said cylinders; grinding stones mounted on each of said body members and adapted to work on the bore of one of said cylinders independently of the work of the stones of another body member on another cylinder, a yoke rigidly connecting the opposing ends of adjacent body members, and adjusting means for positively adjusting the stones radially on each body member independently of the radial adjustment of stones on another body member, the adjusting means for said stones being accessible at the outer ends of said body members. 85 90

In testimony whereof I sign this specification. 95
